(57) **CLAIM**

The ornamental design for a beverage sleeve, as shown and described.

DESCRIPTION

FIG. 1 is a top back right isometric view of the beverage sleeve.

FIG. 2 is a back side elevation view thereof.

FIG. 3 is a top side elevation view thereof.

FIG. 4 is a bottom side elevation view thereof.

FIG. 5 is a top right back isometric view of the beverage sleeve shown in an environmental use.

FIG. 6 is a top front left isometric view of the beverage sleeve; and,

FIG. 7 is a front side elevation view thereof.

The dashed broken lines in FIG. 5 showing a beverage container illustrate environment and from no part of the claimed design.

All other dashed broken lines show portions of the beverage sleeve that form no part of the claimed design. The dot-dashed broken lines illustrate the bounds of the claimed design and form no part of the claimed design.

1 Claim, 7 Drawing Sheets
